UNITED STATES PATENT OFFICE.

THOMAS IRVING POTTER, OF PORTLAND, OREGON, ASSIGNOR TO COIN MACHINE MANUFACTURING COMPANY, OF PORTLAND, OREGON, A CORPORATION OF OREGON.

COIN-EJECTING MACHINE.

1,216,606.

Specification of Letters Patent. Patented Feb. 20, 1917.

Application filed August 11, 1914. Serial No. 856,260.

To all whom it may concern:

Be it known that I, THOMAS IRVING POTTER, a citizen of the United States, residing at Portland, in the county of Multnomah and State of Oregon, have invented certain new and useful Improvements in Coin-Ejecting Machines; and I do hereby declare the following to be a full, clear, and exact description of the same, reference being had 10 to the accompanying drawings, forming part of this specification, and to the figures and letters of reference marked thereon.

The present invention relates to that type of coin handling machines adapted for the paying out of sums of money either as change in commercial transactions or in the payment of given sums of money, by the manipulation of suitable keys which, through mechanical connections are adapted 15 to eject the sum of money indicated by the operated keys. The objects of the invention are to provide an arrangement whereby mental calculation or effort shall be eliminated as far as possible, and in accomplishing 20 this object provision is made whereby the operator will have displayed before him coins in the form of key tips or finger pieces which correspond to the coins which will be ejected by the machine, thus relieving the 25 mind of the operator of the necessity of translating the idea of the coin desired into a number representing the denomination of such coin or coins.

Referring to the accompanying drawings,

Figure 1 is a top plan view of a coin ejecting machine embodying the present improvements.

Fig. 2 is a front elevation of the same.

Fig. 3 is a top plan view of the keyboard alone with the machine frame in section.

Fig. 4 is an elevation looking at the right hand side of the parts shown in Fig. 3.

Like reference numerals indicate similar 45 parts in all figures.

The machine illustrated is in its mechanical embodiment of the coin holding and ejecting mechanism similar to machines now on the market and substantially as such as is embodied in my contemporaneous application filed August 28, 1913, Serial No. 787,126. It comprises a frame 1 having coin stacks or holders 10 at the bottom of which stacks are suitable ejectors adapted to be 50

operated by the manipulation of key levers 55 2 carrying at their outer ends suitable finger pieces by which the levers are depressed, when coins are to be ejected. The particular mechanical connections for accomplishing these results is immaterial, in so far as 60 the present invention is concerned, although it is desirable that the key levers 2 shall be so arranged that their finger pieces may be grouped in proper sequence for manipulation by the fingers of one hand in the ejecting 65 of a sum of money from the smallest to the greatest amount adapted to be handled by the machine.

The finger pieces on the key levers 2, in accordance with the present invention are 70 formed by coins of the denomination which will be ejected by the manipulation of the key levers on which the finger pieces are mounted, and where a plurality of such coins are ejected by the manipulation of a 75 single lever, the finger piece is formed by a corresponding number of coins. As shown in the drawings, the coins are indicated by the reference numeral 5, and as will be noted from Fig. 3, the key levers carrying finger 80 pieces formed by the fifty cent, twenty-five cent, ten cent and five cent coins are all mounted individually on their own levers. Inasmuch as the one cent coins, in order to make proper fractional change, must be ejected either singly or in groups of two and four 85 coins respectively, the finger piece for one lever is formed by a single penny, that for another lever is formed by two pennies and that for still another lever is formed by four 90 pennies. The coins forming the finger pieces are held in place on the levers by clips 3 having upwardly extending coin embracing lugs or fingers 3', the clips being formed in sections adapted to be clamped to opposite sides of the levers 2, whereby the lugs or fingers 3' may be drawn together so as to tightly embrace the coins when the two sides of the clips are secured by a single fastening screw 6, passing through the end of 100 the lever.

The invention is particularly applicable for use in connection with the key levers for ejecting fractional currency, and in the accompanying drawings where levers are employed for coins of higher denomination, to-wit: dollars, number plates 11 are preferably employed for the dollar key levers, and

these number plates are held in place by clips 4 on the dollar key levers, although it will be understood that the finger pieces for the dollar levers may be formed of gold coins, as in the case of fractional currency, although this may not be necessary or is undesirable because of the value of the coins, or because of the further fact that these levers are not so frequently used as are the levers for discharging fractional currency.

With a coin paying machine embodying the present improvements, the operator manipulates the machine by touching coins of the desired denomination and is relieved of the necessity of mentally translating the value of the coin into a number on the finger keys, as heretofore. The manipulation of the machine thus becomes closely akin to the act of making change by selecting coins from a table or counter in the customary way, whereby the making of change is considerably simplified and the liability of error reduced to a minimum.

Having thus described my invention, what

I claim as new and desire to secure by Letters Patent, is,—

1. In a coin ejecting machine, the combination with levers controlling the ejection of coins, of finger pieces through which said levers are manipulated formed by coins corresponding to the coins ejected by the manipulation of said levers, and clips having coin embracing lugs for retaining the coins constituting the finger pieces in position.

2. In a coin ejecting machine, the combination with levers controlling the ejection of coins, sectional clips mounted on said levers and having upwardly projecting lugs, screws for securing the sections of said clips together and coins constituting finger pieces embraced by said lugs, said coins corresponding to the coins ejected by the manipulation of the levers on which the finger piece coins are mounted.

THOMAS IRVING POTTER.
